UNITED STATES PATENT OFFICE.

JONATHAN ALBERT LYONS, OF NUEVITAS, CUBA.

SHOE-TONGUE.

SPECIFICATION forming part of Letters Patent No. 748,197, dated December 29, 1903.

Application filed July 8, 1903. Serial No. 164,721. (No model.)

To all whom it may concern:

Be it known that I, JONATHAN ALBERT LYONS, a citizen of the United States, residing at Nuevitas, Cuba, have invented certain new and useful Improvements in Shoe-Tongues; and I do hereby declare the following to be a full, clear, and exact description of the invention, such as will enable others skilled in the art to which it appertains to make and use the same.

This invention relates to tongues for shoes; and it consists of an attachment for engaging with the shoe-tie and holding the tongue in position.

In the drawings, Figure 1 is a front view of a portion of a shoe-tongue provided with an attachment according to this invention. Fig. 2 is a side view of the same. Fig. 3 is a plan view of the attachment before being applied to the tongue.

A is a portion of a shoe-tongue.

B is a plate of thin sheet metal having a loop b struck up and partially punched out from its middle part. The side portions of the plate have flattened folds c, which permit the formation of the said loop. The corners of the plate have sharp triangular tangs d, which are inserted through the leather tongue and which secure the said plate to it.

A portion of the shoe tie or lace is passed through the loop b, so that the tongue is held in its central position, where it is most comfortable to the wearer.

What I claim is—

The combination, with a shoe-tongue, of a plate having a loop struck up from its middle portion and having flattened folds in its side portions, and means for securing the said plate to the said tongue.

In testimony whereof I affix my signature in presence of two witnesses.

JONATHAN ALBERT LYONS.
